UNITED STATES PATENT OFFICE.

OTTO G. GILDE, OF ALTOONA, PENNSYLVANIA.

MAUSOLEUM.

Application filed April 20, 1927. Serial No. 185,220.

My present invention has reference to a mausoleum designed to provide a monument to perpetuate the memory of the departed.

5 An object is the provision of a mausoleum constructed of concrete sections, polished or otherwise treated to present a highly ornamental, stately and refined but unostentatious monument that shall provide a befitting 60 memorial for the dead.

A further object is the provision of a mausoleum that is constructed of sections which provide a tomb for the casket of a deceased person and which sections while effectively 15 sealed together have means for admitting outside air into the tomb without permitting the entrance of dirt, insects, etc., thereinto, and whereby the air pressure in the tomb is equal to the outside pressure of the air so 20 that the casket will be thus effectively and indefinitely preserved.

A further object is the provision of a mausoleum that comprises a concrete base designed to be arranged upon the ground surface 25 of a burial ground, and which base is provided with a metal compartment that is normally closed by a door, the said compartment providing for the reception of tools employed in a graveyard, while resting on the base and securely affixed thereto there is 30 the hollow body portion of the improvement, the latter, however, being provided with a base having upstanding lugs on which the casket rests, the body being closed by a sealing slab, while resting on and secured to 35 these members there is the ornamental top slab of the improvement, there being air conducting passages between the base, the body and the top that are suitably screened to prevent the passage of dirt, insects and the like through such passages, all of the constructions being of a highly ornamental but of 40 unostentatious appearance.

A still further object is the provision of a 45 mausoleum in which any desired number of casket containing bodies may be superimposed one over the other so that the several deceased members of a family may repose in the tombs thus provided by the mausoleum.

50 The invention will be best understood from a consideration of the following detailed description taken in connection with the accompanying drawings which form part of this specification, it being understood 55 that the invention is not to be confined to the

precise showing of the drawings, and that the same may be changed or modified so long as such changes and modifications mark no material departure from the salient features of the invention as expressed in the appended 60 claims.

In the drawings:

Figure 1 is a side elevation of a mausoleum in accordance with this invention.

Figure 2 is a sectional view approximately 65 on the line 2—2 of Figure 1.

Figure 3 is a sectional view approximately on the line 3—3 of Figure 2.

Figure 4 is a bottom plan view of the top 70 slab or cover.

Figure 5 is a sectional view approximately on the line 5—5 of Figure 3.

Figure 6 is a sectional view approximately on the line 6—6 of Figure 3.

Figure 7 is a side elevation, with parts in 75 section, illustrating a modified form of the mausoleum.

Figure 8 is a sectional view approximately on the line 8—8 of Figure 7.

Figure 9 is a detail sectional view to illustrate the manner in which the screen is 80 arranged in one of the air conducting ports or passages.

Figure 10 is a perspective view of the 85 screen.

Preferably the base member or slab of my improvement is cast or molded at the place where the mausoleum is to be erected, while the remainder of the construction is cast in a suitable plant or factory and shipped therefrom. The improvement is wholly constructed of concrete, except for certain parts which will be referred to in this description. All of the concrete parts of the improvement have their outer faces rubbed and polished to present smooth white surfaces and, if desired, these exposed surfaces may be marbleized.

The base 1 comprises a substantially rectangular member, that is the slab is centrally formed with an opening therethrough, and the outer edges of the base are formed with an ogee molding or otherwise ornamenteally shaped. The corners of the base slab have upstanding round portions thereon formed with annular depressions 2 for the reception of pots or vases containing flowers. The base slab 1, has one of its ends provided with a substantially rectangular opening that communicates with the hol- 100 105 110

low body of the base, and in this opening there is arranged a rectangular casing 3 of copper or some other suitable metal which is not susceptible to deterioration under 5 weather conditions. The casing 3 on the sides thereof has outstanding ears 4 which are embedded in the base 1 in the process of manufacture of the base and these ears have openings therethrough through which certain 10 portions 5 of the plastic base pass and which portions 5 serve as anchors for the ears and for the casing 3. The outer end of the casing 3 is shaped to conform to the molded edge of the base, and this end of the casing has hinged thereto a copper or similar metal cover 6 shaped to correspond to the contour of the base. The cover is normally locked by means 7, Figures 2 and 3. The casing provides a means whereby tools 15 or other implements employed in a burial ground may be housed, while the locked cover 6 prevents the surreptitious removal of such tools.

The concrete body member 8 of the improvement is of rectangular formation, the same having its upper and lower edges formed with ornamental moldings. The body 8 rests directly on the base. In the showing of Figures 1 to 6, the lower corners 20 of the body are recessed so that the bottom 9 of the said body is partly received in the opening of the base slab and contacts with the inner edges provided thereby. Obviously other interengaging means may be provided 25 between the base and body, as for instance, these members may be formed with interengaging tongues and grooves. The sides and ends of the body are preferably formed with depressed panels 10, and these panels 30 may be given a rough or other ornamental finish to contrast with the outer surface of the body proper. In the side panels there are removable metal name plates 11. These name plates are secured in the panels 40 through the medium of bolts 12 that have squared portions passing through the ends of the said plates 11, and having their shanks passing through the sides of the body 8. The inner face of the body has depressions 45 in which the shanks of the bolts enter and these depressions also provide pockets for the nuts 13 that are screwed on the bolts.

The bottom 9 of the body is provided with upstanding transverse ribs 14. Preferably two of such ribs are employed and these ribs provide supports for a casket 15 which is received in the body. In this manner it will be noted that the casket is supported above the bottom 9 of the body so that air can freely circulate around the casket being admitted to the interior of the body in a manner which will hereinafter be described. The body is adhesively connected to the base, preferably by cementing these members together.

After the casket has been arranged in the body 8, the body is sealed by a top slab 16. This slab has its edges beveled and enters a continuous depression on the inner wall of the top of the body, the side wall provided by the depression being also beveled. The slab is sealed in this depression 17 by a plastic cement 18. The sealing slab 16 is formed with hand holds 19 adjacent to the ends thereof. In the showing of Figure 3 of the drawings, these hand holds are provided by recessing the upper face of the sealing slab adjacent to the ends thereof, the recesses 20 having their side walls rounded and entering below the hand holds 19, so that the hand holds have their outer edges rounded and can be firmly gripped by the insertion of the hands of the operator in the recesses.

There is preferably embedded in the top of the body 8 outstanding dowel pins 21 that enter openings in the top or cover slab 22 of the improvement. Obviously other interengaging means than the dowels and holes may be provided between the body and the cap slab 22, and when the cap slab is arranged on the body it also rests on the sealing slab 16. The cap slab is secured on the body and on the portion of the sealing slab with which it contacts through the medium of a plastic cement or the like.

The cap slab 22 has its under face hollow, that is, the said under face of the cap slab has a longitudinal depression 23 therein. The outer edges of the cap slab are formed with moldings, as clearly disclosed by the drawings.

As far as the description has progressed it will be apparent that I have produced a mausoleum which can be cheaply constructed and easily erected, which provides an ornamental appearance without being ostentatious, and in which the casket and the remains therein will be indefinitely preserved. The improvement in reality provides a sarcophagus.

It is necessary in order to insure the preservation of the casket that air be admitted into the tomb provided by the body 8 and to provide for this body 8, at desired spaced intervals is formed with vertically arranged air conducting holes or passages 24, there being transverse passages 25 that communicate with the passages 24 and with the interior or tomb provided by the body. These lateral passages 24 have arranged therein screens to prevent the entrance of dust, insects or the like into the tomb. These screens are best illustrated by Figures 9 and 10 of the drawings. By reference to these figures it will be seen that I employ split spring rings 26 and secured on these split spring rings is closely woven wire mesh 27. The split rings when inserted in the passages 25 will expand, drawing the mesh 27 taut and the frictional engagement between the rings and the walls

of the passages effectively sustains the screens in such passages.

The vertical air conducting passages 24 are closed or sealed when the cap slab is arranged on the body 8. The passages 24 on the sides of the body communicate with angle passages 24' in the cap slab 22. The passages 24' establish a communication between the chamber 23 in the cap slab, and the entrance of air into the cap slab prevents the sweating thereof and preserves the slab. In addition to the central and side passages 24 the body 8 is provided with corner air conducting passages 28 that establish communications between the hollow base and angle passages 28' in the cap slab 22. The passages 24' and 28 have arranged therein screens 29 similar to those previously described, and all of the air conducting passages in the body have like screens 30 arranged therein. By this arrangement it will be seen that air will freely circulate between the base, the hollow cap slab and enter the body 8 so that the air will circulate around the casket.

It is within the province of this invention and my intention to produce a mausoleum that shall provide tombs for a number of deceased persons in a family or for the relatives of the family and, therefore, in Figures 8 and 9 of the drawings, I have shown a number of bodies similar to the body 8 arranged in superimposed relation, that is, one on the other. In this showing the base slab 31 is substantially similar in construction to the base slab 1, except that the said base slab 31 has a top portion 32 provided with upstanding transverse ribs 33. The body 34 that rests on the base has a depending continuous tongue 35 that is received in a continuous groove 36 in the top of the base. These interengaging parts are connected together by a sealing cement 37. The superimposed body 38 has a continuous depending tongue 39 received in a continuous groove 40 in the top of the substantially rectangular body 34. It is to be noted that neither of the bodies 34 and 38 are provided with bottom walls but each of these bodies has a continuous inner depression at its upper edge, the inner or side wall of which being arranged at an angle. In each of these depressions there is seated a sealing slab 41. The slabs 41 are sealed in the grooves by plastic cement 42. The sealing slabs 41 in this instance are provided with upstanding transversely arranged ribs 43 having curved openings therethrough which enter the body as indicated by the numerals 44. These openings provide the ribs 43 with hand holds or grips and the said ribs serve as supports for caskets 45. The cap slab 46 is provided with a continuous tongue 47 that is received in the continuous groove in the upper or outer face of the body 38, the

tongue being secured in the groove by a plastic cement 48. The body members 34 and 38 have aligning central and side vertical air conducting openings 49 affording air passages and these passages communicate with passages 50 in the top 32 of the hollow base slab 31, and the end passages are closed by the cap slab while the side passages communicate with angle passages 52 in the said cap slab. The vertical passages 49 in the body members 34 and 38 are intercepted by transverse passages 51 that communicate with the interior or tombs of the bodies. The body members 34 and 38 are also provided with corner air conducting passages 80 that communicate with the angle air conducting passages 52 in the cap slab 46 and that communicate with the hollow inner face 53 of the said cap slab 46. In the openings 52 there are screens 54 similar to the screens previously described and likewise in the lateral or angle passages 51 there are similar screens 55. Also in the passages 50 there are like screens 56. These screens, of course, are to prevent the entrance of insects or extraneous matter into the tombs or into the hollow portion of the cap slab. Of course, the construction just described is polished and brightened or otherwise ornamented, the same being formed with the beads or molds 95 substantially similar to those previously described. Likewise the sides and edges of the body members 34 and 38 are depressed to form panels and name plates are removably secured in certain of these panels. While 100 not shown in the drawings, the hollow base is provided with an inlet opening in which there is arranged a casing similar to the casing 3, the said casing being, of course, closed by a hinged door which is normally 105 locked.

It is believed that the foregoing description, when carefully read in connection with the accompanying drawings will fully set forth my construction and the advantages 110 thereof to those skilled in the art to which such invention relates so that further detailed description will not be required.

While I have illustrated and set forth that a single casket is arranged in each tomb of 115 the mausoleum, it is, of course, to be understood that the mausoleums may be of such widths as to accommodate two or more caskets in each tomb thereof. Also it is to be understood that all parts of the mausoleum 120 and base may be constructed of other material than concrete, that is to say, the same may be formed of cement, clay products, marble, metal, etc., either polished or unpolished. Further all parts constituting the 125 mausoleum may be constructed at the place where the mausoleum is to be erected or at a factory or like place of manufacture or erection from which place the slabs and foundation could be turned out in uniform 130

molds by the parties casting the mausoleum and shipped for prompt delivery at the place where the mausoleum is to be erected.

Having described the invention, I claim:

- 5 1. A mausoleum constructed of concrete whose outer surface is polished, and which comprises a hollow base to rest on a ground surface, a hollow body resting on the base, upstanding ribs in the body to afford a support for a casket, a sealing slab for the body, a cap slab arranged over the body, interengaging means between the body, base and cap slab, plastic means adhesively connecting the body to the base, the cap slab and the sealing slab, and means for admitting air through the hollow base into the body.
- 10 2. A mausoleum constructed of concrete whose outer surface is ornamented and polished, and which comprises a hollow base, a hollow body resting on the base, upstanding ribs in the bottom of the body to afford a rest for a casket, said body having its inner edge, at the top thereof formed with a continuous groove, a sealing slab seated in the groove and sealed to the body, a cap slab having its inner face recessed and which rests on the sealing slab and on the body, interengaging means between the cap slab and the body, and said cap slab being sealed to the body, said body and cap slab having aligning openings that communicate with the hollow base and with the interior of the body and the depressed portion of the cap slab, a split spring ring in said openings, and a wire mesh arranged over each of the rings and designed to be drawn taut upon the expansion of the rings.
- 15 3. A mausoleum including a hollow base, a sarcophagus resting on and sealed to the base, means for admitting air through the base into the sarcophagus, said base having an opening at one end thereof communicating with the interior of said base, a metal casing arranged in the opening, apertured ears extending from the sides of the casing embedded in the base therethrough, a hinged cover for the casing, and means for locking the cover on the bottom of the casing.
- 20 4. A mausoleum including a hollow base, a body resting on the base and sealed thereto, a sealing slab closing the open top of the body, and a hollow cap slab arranged over the sealing slab and on the top of the body and sealed to the latter, said body having vertical air passages therethrough communicating with the hollow base and having transverse ports communicating with the interior of the body and with said passages, and said cap slab having air passages registering with the air passages in the body and communicating with the hollow interior of the cap slab, screens in said passages and ports and said passages and ports establishing a continuous circulation of air between the base, body and cap slab.
- 25 5. A mausoleum comprising a hollow base, a body resting on the base and sealed thereto, a sealing slab closing the open top of the body, and a hollow cap slab arranged over the sealing slab and on the top of the body and sealed to the latter, said body having vertical air passages therethrough communicating with the hollow base and having transverse ports communicating with the interior of the body and with said passages, and said cap slab having air passages registering with the air passages in the body and communicating with the hollow interior of the cap slab, screens in said passages and ports and said passages and ports establishing a continuous circulation of air between the base, body and cap slab.
- 30 6. A mausoleum constructed of concrete whose outer surface is ornamented and polished, and which comprises a hollow base, a hollow body resting on the base, upstanding ribs in the bottom of the body to afford a rest for a casket, said body having its inner edge, at the top thereof formed with a continuous groove, a sealing slab seated in the groove and sealed to the body, a cap slab
